UNITED STATES PATENT OFFICE.

HARRISON W. HICKS, OF ALEXANDRIA, INDIANA, ASSIGNOR TO THE HUNTINGTON SPECIALTY COMPANY, OF HUNTINGTON, INDIANA, A CORPORATION OF INDIANA.

CLOCK.

1,107,947.

Specification of Letters Patent. Patented Aug. 18, 1914.

Application filed June 18, 1911, Serial No. 633,631. Renewed November 28, 1913. Serial No. 803,600.

To all whom it may concern:

Be it known that I, HARRISON W. HICKS, a citizen of the United States, residing at Alexandria, in the county of Madison and 5 State of Indiana, have invented a new and useful Clock, of which the following is a specification.

This invention relates to improvements in 10 clocks, the primary object of the invention being the provision of a clock the hour hand of which is controlled through the medium of the minute hand, the said minute hand being operated through the means of a watch movement mounted in one end thereof 15 and provided with a counter balancing pendulum or pendant, which is controlled by the movement of the watch, so as to rotate the minute hand, and consequently operate the hour hand.

20 A further object of the invention is the provision of what is termed a mysterious clock, that is a clock in which the operating mechanism thereof, is so hidden that apparently the only objects in view, are the dial 25 plate, hour hand and minute hand.

With the foregoing and other objects in view which will appear as the description proceeds, the invention resides in the combination and arrangement of parts and in the 30 details of construction hereinafter described and claimed, it being understood that changes in the precise embodiment of invention herein disclosed can be made within the scope of what is claimed without departing 35 from the spirit of the invention.

In the drawings—Figure 1 is a front elevation of a clock constructed according to 40 and embodying this invention. Fig. 2 is a vertical cross section through the same with the shaft or support carrying the minute hand and hour hand in section. Fig. 3 is an 45 enlarged front elevation of the lower portion and center of the minute hand taken from the rear and showing the clock mechanism. Fig. 4 is an elevation of the main arbor removed.

Referring to the drawings, the numeral 1 designates the dial of the clock, which in this 50 instance is a sheet of transparent material, such for instance as glass, and mounted in the front portion thereof is a concave disk 2, provided with an opening for the reception of a sleeve 3, which is provided with a cylindrical socket therethrough and with a set 55 screw 4, for the immovable reception of the

flat end of the arbor or shaft A, thus forming a support for the elements of the clock. This shaft has secured to its outer end a locking sleeve 5 by means of the set screw 8, the sleeve 7 being rotatably mounted upon 60 the smooth portion a' of the arbor or shaft A, so that the same may rotate thereon.

Carried by and rotatable with the sleeve 7 is the minute hand 8' of the clock, and formed integral upon the rear end of the 65 sleeve 7 is a small pinion 9, connected at all times with the large pinion 10, carried by the shaft 11, which is journaled in the depending bracket 12 secured upon the squared portion of the shaft A. The shaft 11 also 70 has mounted thereon the small pinion 13, which is connected at all times with the large pinion 14, keyed upon the forward end of the sleeve 15, carrying the hour hand 16. This sleeve 15 is rotatably mounted upon the long 75 portion 15' secured to and carried by the shaft or support A.

The lower end of the minute hand is provided with the crescent shaped portion 17, which has provided upon its inner face the 80 aperture or opening 18, whose center is in a direct line with the center of the axis of the minute hand, and in which is adapted to removably fit the watch movement 19, whose hour hand arbor 20, is connected to the sleeve 85 21 of the rod 23, by means of the set screw 22. Carried upon the lower or extreme end of the arm or rod 23 is a counter balance or weight 24, which in this case is shown in the form of a ball or sphere, but which however 90 may be made in a flat disk shape if so desired.

From the foregoing description taken in connection with the drawings it is evident that a clock, which apparently has no actuating mechanism, is provided, the said actuating mechanism being a watch movement in the lower short end or non-pointing end of the minute hand, the said watch movement being so disposed within the 100 same, that portions of said movement on opposite sides of the longitudinal axis of the hands exactly balance each other. In this form of clock, it will be seen that as the clock mechanism elevates the weight, the 105 center of gravity is shifted, and the equilibrium of the hand destroyed, corresponding change being made in the position of the hand, as the reaction of the first movement and the weight allowed to maintain its 110

center of gravity. This counter balancing effect being a constant one, the action of the mechanism, or the clock movement in its endeavor to force around the weight, is bound to react upon the minute hand, causing it to constantly and uniformly shift its position and by so doing indicate the time and minutes upon the dial. Thus as the minute hand is moved and is geared to move twelve times as rapidly as the hour hand 16, the minute hand will indicate the minutes, and the hour hand will indicate the hour.

What is claimed is:

15. The herein described mysterious clock, having a dial, a concaved disk carried by the dial, a sleeve disposed concentrically of the disk, a rod having a plurality of varying diametered portions detachably connected and supported by said sleeve, an hour hand,
20. an hour hand sleeve arbor carried upon one portion of said rod and carrying the hour hand, a bracket depending from the inter-

mediate portion of the rod, a minute hand, a sleeve carrying the minute hand rotatably mounted upon the end portion of the rod, a gear carried by said latter sleeve, a shaft journaled in the bracket, two gears one upon each end of said shaft, and upon each side of the bracket, one of said gears being in mesh with the gear of the minute hand sleeve, and a gear upon the hour hand sleeve and in mesh at all times with the other gear of the shaft, and a watch movement having a weight attached to its hour hand arbor, disposed in the non-pointing end of the minute hand to cause the rotation of the minute hand and the actuation of the hour hand.

In testimony that I claim the foregoing as my own, I have hereto affixed my signature in the presence of two witnesses.

HARRISON W. HICKS.
